UNITED STATES PATENT OFFICE.

JOSEPH A. KLOEB AND RUDOLPH B. KLOEB, OF SWAYZEE, INDIANA.

GASEOUS-FUEL BURNER.

1,285,232.

Specification of Letters Patent. Patented Nov. 19, 1918.

Application filed July 19, 1918. Serial No. 245,652.

To all whom it may concern:

Be it known that we, JOSEPH A. KLOEB and RUDOLPH B. KLOEB, citizens of the United States, residing at Swayzee, in the county of Grant and State of Indiana, have invented certain new and useful Improvements in Gaseous-Fuel Burners, of which the following is a specification.

This invention relates to the subject of 10 gaseous fuel burners, and more particularly to an improvement in combined generators and burners adapted for general heating purposes.

One of the objects of the present invention is to provide a simple, practical and reliable structure which will effectively convert the liquid fuel into a vapor whereby when the same is mixed with air it will form a highly combustible gas whose flame 20 will assist in continuing the process of vaporization to maintain the operation of the burner as long as a supply of fuel is available.

A further object of the invention is to 25 provide a combined generator and burner construction wherein the circulation of the gas and gaseous mixture is relatively free or unobstructed, thus removing to a great extent the possibility of the collection of 30 carbon deposits which would hinder the proper operation of the device. In this connection, it is also proposed to provide a relatively spacious mixing tube wherein the liquid vapor and air may be thoroughly 35 mixed in the proper proportions to form the necessary gaseous mixture, and which mixture is highly heated because of the location of the mixing tube of the device over and above the generating retort where 40 it may be bathed in the flame of the burner.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which—

Figure 1 is a side elevation of the improved generator and burner device.

Fig. 2 is a top plan view thereof.

Fig. 3 is a vertical cross sectional view

taken on the line 3—3 of Fig. 1 looking in 55 the direction of the arrows.

Fig. 4 is a side elevation illustrating a modified form of starting pan which also constitutes a flame spreader for directing the burner flame in opposite directions. 60

Similar reference characters designate corresponding parts throughout the several figures of the drawings.

In carrying the present invention into effect it is proposed to utilize a generating 65 retort which is adapted to receive the liquid fuel from a suitable source of supply, whereby under the influence of heat the fuel will be converted into vapor which when mixed with air may be conveyed to a suitable point 70 with reference to the retort whereby it may be ignited to thereby provide a flame which will not only produce the desired stove or furnace heat but at the same time maintain the generating action in the retort. 75

Accordingly, to this end it is proposed to employ a generator retort designated generally as 1, the same preferably being of a circular or ring-like formation and having a central burner opening 2 and also the 80 annular generating chamber 3 adapted to communicate with a source of fuel supply through the pipe 4, and also provided at a point opposite the pipe 4 with a suitable gas outlet pipe connection 5. For conveniently supporting the entire burner device either in the fire-box of a cook stove or fire-pot of a heating furnace, the said supply pipe 4 and outlet pipe 5 may have fitted thereto suitable supporting brackets 6 which 85 may be adjustably vertically to raise or lower the burner with reference to the surface to be heated, thus enabling the structure to be suitably adjusted to meet the requirements of various heating apparatus. 90

In connection with the gas outlet pipe 5 which communicates with the generator chamber 3 of the retort, it will be observed that the same projects away from the retort in a suitable manner whereby its end portion 7 having therein a lateral jet orifice 8, is disposed a short distance in front of the open mouth of a mixing tube 9 which has the general disposition shown in Figs. 1 and 2 of the drawings, and is of relatively 105 large diameter to provide for the accommodation and thorough mixing of a relatively large volume of gas and air. Furthermore,

it will be observed that the said mixing tube 9 is of goose-neck formation, that is, doubled back upon itself to provide a relatively long heating surface for the gaseous mixture to pass over before it is discharged therefrom, to insure super-heating before ignition.

As shown in the drawings it is proposed to mount the mixing tube so that its downwardly directed burner end 10 fits into the central opening 2 of the retort, whereby the entire tube will lie in close proximity to the upper surface of the retort and receives the full benefit of the flame which causes the generating action within the retort. And, in this connection it will be observed that the intake end of the mixing tube is disposed a sufficient distance beyond the zone of the flame to prevent the igniting of the vapor issuing from the jet orifice 8.

Arranged beneath the retort 1 is a suitable flash pan 11, the same having a swivel connection 12 with the underside of the retort whereby it may be conveniently swung to one side for receiving the priming charge of fuel to start the device, and then swung back into position beneath the retort to give the latter the full benefit of the starting flame when the priming charge is ignited. As shown in Figs. 1 to 3 this flash pan may be of circular formation and will assist in directing the flame issuing from the burner end of the mixing tube through the burner opening 2 upwardly onto the retort and mixing tube itself. However, when it is desired to use the present device in the fire-box of a cook stove, it is desirable to use the type of flame pan 13 shown in Fig. 4 of the drawings. This flame pan 13 is of elongated shape and is especially designed to not only direct the flame upwardly onto the generator retort, but also to the underside of the front and rear lids of the stove.

From the foregoing it will be clear that the liquid fuel, such as kerosene, may be supplied from a suitable tank, not shown, to the pipe 4 from whence it will make its way into the generating chamber 3 of the retort 1 which has been previously heated by the starting flame in the pan 11, and after a short period the liquid fuel in the said chamber 3 will be converted into gas and leave the said chamber through the pipe 5 having the lateral jet orifice 8 which is disposed a short distance from one end thereof and opposite the intake end of the mixing tube 9. In this connection it may be noted that the extremity of the pipe 5 is closed or sealed, and the jet orifice 8 is disposed a suitable distance back from this closed end, whereby the space between the orifice and said end will constitute a pocket which will serve to trap or collect any relatively heavy particles of foreign matter or carbon which might otherwise obstruct the free discharge of vapor through the jet orifice. After the vapor

mixes with the air in the tube 9 the combustible gas thus formed proceeds through the curved portion of the tube 9 to its outlet end 10 in the central burner opening of the retort 1, where it is ignited by the starting flame and the burning of this gas then takes the place of the initial starting flame to continue the heating of the retort and mixing tube 9, to thereby not only maintain the generating action of the retort and super-heat 75 ing effect of gases in the mixing tube, but to produce an extremely hot flame which may be utilized for the desired heating purposes.

Without further description it is thought 80 that the features and advantages of the present invention will be readily apparent, and it will of course be understood that minor changes in the form, proportion and details of construction may be resorted to without departing from the spirit of the invention or scope of the appended claims.

We claim:

1. A gaseous fuel burner comprising a circular retort having an annular generator chamber therein and a central burner opening extending therethrough, a mixing tube arranged above the retort and having one end in communication with the burner opening through the retort, a gas pipe in communication with said chamber and arranged to discharge into one end of the mixing tube, and a flame deflector arranged at the mouth of the burner opening below the retort.

2. A generating burner device including 100 a retort having an annular generator chamber and a central burner opening, a mixing tube arranged above the retort and having its discharge end opening into the central burner opening thereof, and a gas feeding 105 connection between said retort and the intake end of the mixing tube.

3. A generating burner device including a generator having an annular generating chamber and a central burner opening, a 110 fuel supply connection for said generator chamber, a mixing tube doubled upon itself and having its discharge end fitting into the upper end of said burner opening of the retort and also having its intake end disposed 115 beyond the flame zone of the burner, and a gas feeding tube between said generator chamber of the retort and the intake end of the mixing tube, said gas feeding tube having a jet orifice located back from the closed 120 end thereof.

4. A generating burner device including a retort having a generator chamber and oppositely disposed fuel supply and gas feeding pipe connections, a mixing tube carried by 125 the upper side of said retort and having its intake end adapted to receive gas from said gas feeding pipe, and supporting brackets engaging with said oppositely disposed pipe connections for supporting the entire device. 130

5. A generating burner device including a hollow generator-burner ring having a fuel supply connection, a mixing tube carried by the upper side of said ring and discharging 5 downwardly therethrough, a vapor feeding tube having one end connected with said generator while its opposite end is closed and disposed adjacent the intake end of said mixing tube, and said vapor feeding tube 10 having a jet orifice therein, the latter being disposed back from the said closed end of the tube to provide a trap for solid matter.

In testimony whereof we hereunto affix our signatures in the presence of two witnesses.
